INTERNAL COMBUSTION ENGINE

Application filed April 21, 1928. Serial No. 271,794.

Our invention relates to internal combustion engines and aims to provide an improved, simplified and more efficient mechanism of the class described.

5 In the drawings, illustrating by way of example one embodiment of our invention

Fig. 1 is a vertical section, partly diagrammatic, through an engine;

10 Fig. 2 is a similar vertical sectional view of a single cylinder and associated mechanism, being taken in a plane at right angles to that of Fig. 1; and

15 Fig. 3 is a partly diagrammatic view of means illustrating one feature forming a part of our invention.

Referring more particularly to the drawings, the shaft to be driven, hereinafter termed the power-shaft or cam-shaft, and which takes the place of the usual crank-shaft 20 of that type of engine, is indicated at 1, it being supported in suitable bearings in a housing or case 2. Fast upon said shaft is a cam 3, of which there may be one or more depending on the particular number, grouping and 25 positioning of cylinders. Said cam as shown is a radial cam, wherein the effective variations in the cam path formation or formations are in directions radial of, toward and away from, the cam axis, the latter being also the 30 axis of the shaft 1.

Any number of substantially radially disposed cylinders, having reference to the cam axis, may be employed, one or more, and with a plurality of cylinders their distribution 35 circumferentially of the cam axis may be widely varied. Merely for the purpose of illustrating the principles of our invention we have indicated in Fig. 1 eight cylinders 4, 4, etc. equidistantly spaced through the entire 40 360° about the cam axis, and wherein the power stroke of each piston 5, 5, etc. is made to act through one quarter (two-eighths) of one cam revolution, that is, 90° of cam, thus giving a continuous torque on the cam shaft.

45 A continuous torque may similarly be obtained with a greater or less number of cylinders, whether their number is even or odd, the angular extent of cam through which the power stroke is effective being corre- 50 spondingly varied; for example, with nine

cylinders, the power stroke of each would preferably be made to act through two-ninths of a cam revolution, or 80° of cam arc.

As stated, the number, construction, and arrangement of cylinders illustrated is by 55 way of example only. Should it be desired to confine any or all cylinders to the region either above or below the level of the cam axis that may readily be effected and a continuous torque obtained by arranging the 60 cylinders in two or more groups or sets, each radially disposed with respect to the cam axis but each set in a different plane transverse of the latter. For example, with nine 65 cylinders each acting through 80° of cam arc three sets of three cylinders each may be employed, in each set there being one vertical cylinder and one cylinder at each side thereof, spaced 40° , with a cam for each set, each cam set 120° later than the one preceding it 70 in operation. With eight cylinders, the piston of each having a power stroke acting through 90° of cam arc, a desired positioning of all cylinders either above or below the cam axis level and with the retention of a 75 continuous torque on the cam may be provided with two groups or sets of three cylinders each and one of two, in any desired order, employing three cams, or with four sets of two cylinders each (V-type motor), the 80 latter using one more cam. Numerous other combinations and distributions of cylinders 85 may be employed as may best meet the particular requirements for a given use.

Referring again to the drawings, the piston 5 of each cylinder 4 is constructed and arranged for cooperation with and to drive the cam with which it is associated. The desired operative relation may be variously effected mechanically. In the illustrative embodiment of the drawings the inner end of each connecting-rod or piston-rod 6 is forked as at 7 and receives a stud 8 parallel with the cam axis and carrying three rolls, a roll 9 intermediate the forked portions and rolls 10, 10, one at each side thereof. Said roll 9 cooperates with the inner and central cam surface 11, and said rolls 10, 10 engage in the respective oppositely facing cam paths 12, 12. 95 The particular formation of a cam path 100

12 may vary widely under different circumstances. In the present illustrative embodiment of our invention it may be preferably such as is best seen in Fig. 1, wherein the engine is of the so-called 4-cycle type, each piston passing successively through the cycles of firing and power stroke, of exhaust and herein scavenging, of intake, and of compression. As viewed in said Fig. 1 the cam 10 is rotated in a clockwise direction. The piston at the top central portion of the figure is illustrated substantially at the beginning of its power stroke, which will be effective through 90° of cam arc, to the point in the cam path 12 at present occupied by the piston at the left central portion of the figure. Throughout this portion of the cam path the piston is effective to apply torque upon the cam driving it in a clockwise direction 15 as indicated by the arrow.

There follows, for any given piston, the exhaust and herein a scavenging stroke, effected, in the form illustrated, by that quarter-portion of the cam path between the points occupied by the piston at the left center of the figure and that at the bottom center. At the latter point the piston is shown at the outer end of its exhaust and scavenging stroke. It will be particularly noted that 20 the piston has been caused to travel fully to the outer end or head of the cylinder, substantially into contact with the cylinder head, whereby a practically complete scavenging of waste gases is effected. This result is obtained through the particular formation of the cam path, substantially as illustrated, wherein the path recedes from the cam axis 25 at the end of the scavenging stroke to a distance greater by the length of the compression and firing chamber than at the beginning of the power stroke.

Following the scavenging stroke, whereby substantially all burned gases are forced out of the cylinder, the respective piston descends through its intake stroke, effected by that quadrant of the cam lying between the point occupied by the piston at the bottom center of the figure and that at the right center. In accordance with the volume of charge desired and the corresponding formation of the cam path, the intake stroke of the piston may be varied in extent as desired. As illustrated, each piston is withdrawn or descends during the intake stroke a distance less by the extent of the compression and firing chamber than that to which it travels at the end of a power stroke. This is evident from an inspection of the radial distance of the cam path 12 from the cam axis at the right and left hand center portions of the Fig. 1, respectively. The actual travel of a piston during the intake stroke, as illustrated, is the same as during the power stroke, but since a piston starts its intake stroke from the extreme end of the cylinder it terminates its in-

take stroke at a higher level than at the end of its power stroke. Thus the actual volume of intake of new gas may be the same as in an engine having an unvarying piston stroke such as in a crank-shaft type.

70

Following its intake stroke each piston completes its four cycles by a compression stroke effected through that portion of the cam path 12 lying between the point occupied by the piston of the cylinder at the right center of Fig. 1 and that at the top center, or through the first part of said portion. As illustrated, the compression stroke for each piston is shorter than the power stroke by a distance equal to the depth of the compression or firing chamber. It will thus be seen that the total piston travel during one complete four-cycle operation may be the same as in a crank-shaft type of engine of similar bore in spite of the fact that complete scavenging is herein effected by bringing each piston substantially into contact with the cylinder head during its exhaust stroke.

80

In accordance with our invention it is also possible to bring each piston to the top of its compression stroke well ahead of the point corresponding to the usual dead center occurring in a crank-shaft engine. The cam path 12 as illustrated in Fig. 1 is shaped to effect such action. The piston at the upper right portion of Fig. 1 is at a point where it has not completed its compression stroke; such stroke is completed at a location in the cam path distinctly before the point occupied by the piston at the top center of the figure and approximately mid-way between said two points. From said intermediate point at which the piston reaches the top of its compression stroke, the cam path is given a slight drop, continuing up to the point corresponding to the usual dead center of a crank-shaft, the point occupied by the piston at the top center of Fig. 1. By reason of this construction and arrangement the charge may be fired well ahead of the actual working point of the cam, that is, the point at which torque actually is begun to be applied upon the cam. Thus a set spark may be employed as there can be no kick-back and an early spark on a throttled down engine would have no harmful result, the same being true under the circumstances of a heavy load and low R. P. M.

90

Ignition means for each cylinder is indicated at 13, 13, etc., said means desirably being so positioned and constructed as not to interfere with the approach of a piston into close proximity with the cylinder head during the scavenging stroke and also desirably to provide no objectionable pocket formation from which gases would not be scavenged. While any desired intake and exhaust valve mechanism may be employed we deem it preferable, largely for reasons similar to those stated in connection with the reference to ig-

95

125

nition means, to employ valve mechanism which will least interfere with a complete scavenging of the burned gases. For this purpose a valve system of the sleeve type is 5 considered preferable, whether of the double-sleeve, vertically reciprocating type or the single-sleeve rotary type, or single-sleeve reciprocating and rotating type, or other sleeve valve. For the purposes of illustration we 10 have shown a double-sleeve valve system, see Fig. 2, including an inner sleeve 14 and an outer sleeve 15 actuated through suitable mechanism properly timed. In the present 15 instance we have indicated for this purpose a cam valve-actuating means including, for each of the two sleeves 14, 15, a valve cam 16 with which cooperates a roll 17 at the end of a lifter-rod 18, each of which latter is connected at its upper end to its respective valve sleeve 14 or 15. Said cams are formed and 20 timed to effect opening and closing of the intake and exhaust valve ports at the proper times. In said Fig. 2 the exact timing for the valve sleeves and cams is not indicated. 25 From the foregoing description taken in connection with the drawings it will be observed that a substantially complete scavenging of the burned gases is effected. Because 30 of this scavenging action it will be further understood that a fresh charge will be taken into the cylinders regardless of the presence of a back pressure, if any, against the exhaust gases; so long as the cam-shaft is made 35 to turn the engine cylinders will take in fresh fuel charges, differing in this respect from the usual type of internal combustion engine, wherein if a substantial pressure is built-up on the exhaust, the burned gases merely follow down with the piston during the 40 succeeding intake stroke and out through the intake manifold, resulting in no new charge being taken in. But with a scavenging action such as herein described each piston will 45 develop below-atmospheric pressure in its cylinder regardless of the pressure upon the exhaust. Thus it is clear that the engine of our invention will run with the exhaust under pressure, if that pressure is kept somewhat below the mean effective pressure of a 50 given power stroke, sufficiently below to take care of losses from friction, radiation, etc. Such being the case, it is further apparent 55 that if some exterior force be applied upon the cam shaft to keep it turning, the engine will continue to take in fresh fuel charges in each cylinder and to fire them even should a pressure be applied on the exhaust exceeding the mean effective pressure of a given power stroke. An example of such external application of force arises where the engine of our 60 invention is employed in an automobile and is used to partially brake the latter while descending a grade; so long as the driving wheels of the automobile turn and the engine 65 and driving wheels are operatively connected

through transmission and clutch, the engine parts must continue to function, that is the cam continues to rotate and the pistons and valves to move. Since it has been shown that a fresh fuel charge must enter the cylinders on the intake stroke regardless of the pressure upon the exhaust it will be understood that if, through suitable means, a pressure against the exhaust is created, such pressure may be built up to a point higher 70 than the mean effective pressure of a given power stroke, especially under the condition of a closed throttle. In this manner an extremely efficient braking action may be applied to the engine, of a strictly non-frictional type. 75

Accordingly our invention contemplates the provision of means for creating a pressure upon the exhaust preferably controllable at will of one or more of the engine cylinders. 80 Any suitable means may be employed for this purpose, for example such as illustrated in Fig. 3 and which, as shown, is particularly applicable to the engine as employed in an automobile. Where a pressure is to be applied against the exhaust of all cylinders, the control mechanism may conveniently be associated with the exhaust manifold of the engine, or it may be otherwise located, or 85 separately controllable means may be provided for each or any number of cylinders. In said Fig. 3, we have shown a valve 19 in the path 20 of the exhaust, said valve having a seat 21 onto which it may be moved to retard or temporarily block the exhaust and 90 cause a back-pressure to be built up against it. Any suitable means may be provided for operating this exhaust-pressure controlling device, automatic or otherwise, and herein we have illustrated means for operating the 95 same under control of the operator. The slidably-supported valve stem 22 is pivotally attached at its outer end, as at 23, to a lever 24 hung upon a stationary part, as at 25. The free end of said lever 25 is in turn pivotally connected, as at 26, to one end of a foot-operable push-rod 27, the other end of which is swingably supported by an arm 28 pivotally hung upon a fixed support, as at 29. The valve is normally retained in open position, allowing a free exhaust, by means of a 100 suitable spring 30. It will be noted that the mechanical efficiency of the mechanism illustrated by way of example is high, approximately one to four, due to the location of the point of connection 23 of the valve-stem near the fulcrum point 25 of the lever 24; thus a 105 pressure of 25 pounds, for example applied to the push-rod 27 will effect substantially 110 100 pounds pressure on the valve, to create 115 a like pressure against the exhaust. 120 With such exhaust-pressure-controlling means applied to an automobile engine, it is true that if said means is employed to bring the car to a full stop the engine would stall. 125

But since the engine clutch must be left engaged to render said means effective, said pressure controlling means may conveniently be located for operation by the operator's 5 clutch foot, and just before the car is brought to a complete stop by the exhaust pressure brake means the latter may be released and the clutch disengaged with the same foot which was previously used to operate the 10 exhaust pressure means, permitting the engine to continue in operation as prior to the application of the pressure against its exhaust.

Obviously there is substantially no wear with a brake applied in the manner described, 15 the action being non-frictional in nature, as contrasted, for example, with the action of rubbing surfaces as in a usual mechanical brake. While we have illustrated and described one means of applying the non-frictional brake action it may be applied in various other ways, including for example the provision of a positive cam on the valve illustrated together with a safety-valve set for a given pressure, or by the provision of a 25 cam constructed and arranged to operate with as many cylinders as desired under any particular circumstances, these likewise exhausting against a set safety-valve mechanism.

30 We have previously stated that the engine will operate with its exhaust under pressure, if that pressure is maintained somewhat below the mean effective pressure of a given power stroke. However, if a much higher 35 pressure of hot inert gas is desired it can be obtained. For example, in an eight cylinder engine less than all of the cylinders, say seven cylinders, may be allowed to exhaust ordinarily under atmospheric pressure and 40 the remaining cylinder or cylinders, in such case the eighth cylinder, may be exhausted against a pressure. Under such circumstances the power stroke of all eight cylinders would be working against the exhaust of 45 one, the resulting pressure obtainable being substantially eight times the mean effective pressure of the power stroke; for instance, if the engine is such that it will operate with all 50 eight cylinders exhausting against 100 pounds pressure, then a pressure of approximately 800 pounds may be developed if seven of the cylinders are allowed to exhaust merely under atmospheric pressure. Intermediate pressures may be obtained by the cutting 55 in or out of one or more additional cylinders to or from an exhaust against pressure.

Having thus described certain illustrative embodiments of our invention it will be understood that the principles thereof may 60 be variously embodied, the invention being in nowise limited to the particular means shown and described its scope being set forth in the following claims.

We claim:

65 1. In an internal combustion engine, one

or more cylinders each having a piston, and means, including provision for substantially complete scavenging of burned gases, whereby a piston may be made to work against a pressure which may be greater than the mean effective pressure of any given power stroke. 70

2. In an internal combustion engine, a main element arranged to be rotated, one or more cylinders, each having a piston operatively connected with said element and in such manner that the exhaust gases are substantially completely scavenged from the cylinder or cylinders, and means whereby the piston or pistons of less than all cylinders may be worked against a pressure higher 80 than the mean effective pressure of any given power stroke or strokes.

3. In an internal combustion engine, a plurality of cylinders and pistons therefor constructed and arranged to effect substantially complete scavenging of the spent gases, in combination with means for causing one or more of the pistons to work against a pressure which may be greater than the mean effective pressure of any given power stroke. 85 90

In testimony whereof, we have signed our names to this specification.

LEON H. BEYTES.
